(57) **CLAIM**

The ornamental design for a motion sensor, as shown and described.

DESCRIPTION

FIG. 1 is a top view of the first embodiment of the motion sensor.

FIG. 2 is a bottom view of the first embodiment of the motion sensor.

FIG. 3 is a front plane view of the first embodiment of the motion sensor.

FIG. 4 is a back plane view of the first embodiment of the motion sensor.

FIG. 5 is a right side view of the first embodiment of the motion sensor.

FIG. 6 is a left side view of the first embodiment of the motion sensor.

FIG. 7 is a perspective view of the first embodiment of the motion sensor.

FIG. 8 is a top view of the second embodiment of the motion sensor.

FIG. 9 is a bottom view of the second embodiment of the motion sensor.

FIG. 10 is a front plane view of the second embodiment of the motion sensor.

FIG. 11 is a back plane view of the second embodiment of the motion sensor.

FIG. 12 is a right side view of the second embodiment of the motion sensor.

FIG. 13 is a left side view of the second embodiment of the motion sensor.

FIG. 14 is a perspective view of the second embodiment of the motion sensor.

FIG. 15 is a top view of the third embodiment of the motion sensor.

FIG. 16 is a bottom view of the third embodiment of the motion sensor.

FIG. 17 is a front plane view of the third embodiment of the motion sensor.

FIG. 18 is a back plane view of the third embodiment of the motion sensor.

FIG. 19 is a right side view of the third embodiment of the motion sensor.

FIG. 20 is a left side view of the third embodiment of the motion sensor; and,

FIG. 21 is a perspective view of the third embodiment of the motion sensor.

The broken lines in the drawings showing portions of the motion sensor are included for the purpose of illustrating environmental structure and form no part of the claimed design.
